D. R. REEFE.
SANITARY CUSPIDOR.

APPLICATION FILED AUG. 4, 1908.

932,174.

Patented Aug. 24, 1909.

UNITED STATES PATENT OFFICE.

DANTES R. REEFE, OF JACKSONVILLE, FLORIDA.

SANITARY CUSPIDOR.

932,174.

Specification of Letters Patent.

Patented Aug. 24, 1909.

Application filed August 4, 1908. Serial No. 446,884.

To all whom it may concern:

Be it known that I, DANTES R. REEFE, a citizen of the United States, residing at Jacksonville, in the county of Duval and 5 State of Florida, have invented a new and useful Improvement in Sanitary Cuspidors, of which the following is a specification.

This invention relates to cuspidors especially adapted to be used in large buildings 10 and railroad cars, the object being to provide a cuspidor with a pair of spring actuated covers for closing the same when not in use so that all danger of any odor escaping from the cuspidor is prevented.

15 Another object of my invention is to provide very novel means for actuating the sliding covers so that they can be easily and quickly operated with the foot.

A further object of the invention is to 20 provide very novel means for locking the covers into open position so that the cuspidor can be used.

25 A further object of the invention is to provide a cuspidor which is exceedingly cheap and simple in construction and one which is adapted to be placed in an opening formed in the floor of a building or car so that it will be out of the way.

With these various objects in view, my 30 invention consists in the novel features of construction and arrangement of parts herein-after fully described and claimed.

In the drawings forming a part of this specification:—Figure 1 is a side elevation 35 of my improved cuspidor showing the application of the same. Fig. 2 is a section taken on the line 2—2 of Fig. 1. Fig. 3 is a section taken on the line 3—3 of Fig. 1. Fig. 4 is a detail plan view of the top of the cuspidor showing the slot, and Fig. 5 is a perspective view of the operating bar and guide rail.

In carrying out my improved invention, I 45 employ a U-shaped frame A adapted to be arranged within an opening formed in the floor and which is provided with a central opening A' in which is secured a funnel shaped cuspidor B to which is connected a drain pipe C which is adapted to be connected 50 to a sewer pipe. Secured on the frame A flush with the side edges are strips D on which is secured a plate E the edges of which extend outwardly beyond the same and are provided with openings through 55 which screws E' are adapted to pass for securing it on the floor. The plate is provided

with a central opening E⁴ in vertical alinement with the cuspidor under which on the frame is mounted a pair of plates F F' forming a cover for the cuspidor which are 60 provided with outwardly extending eyes G adjacent their ends which are connected together by coil springs H for normally holding the plates together so as to completely close the cuspidor. Secured to the outer 65 ends of the plates F and F' are the ends of a chain I which pass over pulleys J, J' arranged on top of the frame A and over pulleys K and K' arranged on the side of the frame, the pulley K being arranged 70 centrally of the frame.

The plate E is provided with a slot E² over the pulley K' having an offset portion E³ at one end in which is adapted to fit an operating bar L which is slidably mounted 75 in the slot for locking the same, the bar being connected to the chain as shown at L' and is provided with a slot L² in which works a guide rail M secured to the side of the frame for guiding the operating bar 80 when moved and it will be seen that by pressing on the knob L³ secured to the upper end of the bar L the plates forming the cover will be drawn apart and by simply forcing the bar into the offset portion E³ the plates 85 will be locked into an open position so that the cuspidor can be used and after it has been used it is only necessary to force the bar out of the offset portion and the springs will return the plates so as to close the cuspidor. The slot in the operating bar is of 90 such a size that there will be allowed considerable lateral movement of the bar on the rail so as to allow the bar to be pushed into the offset portion and it will be seen 95 that by this arrangement the sliding covers can be easily and quickly opened and closed by the foot.

From the foregoing description, it will be seen that I have provided a cuspidor which 100 is thoroughly sanitary and one which will be out of the way thereby saving a great deal of trouble and time.

What I claim is:—

In a cuspidor of the kind described, the 105 combination with a frame, of a cuspidor carried by the frame provided with a drain pipe, strips carried by the frame, a plate carried by the strips provided with an opening in vertical alinement with the cuspidor, 110 said plate being provided with a slot having offset portion, a pair of cover plates con-

nected together by coil springs mounted on the frame over the cuspidor, pulleys mounted on the ends of the frame, a chain working over said pulleys having its ends connected to said plates, a guide rail secured to the frame under the slot, an operating bar connected to the chain provided with a slot working over said guide rail, and extending

through the slot of the plate for operating said chain, said operating bar being adapted to be forced into the offset portion of the slot to hold the cover plates apart.

DANTES R. REEFE.
